CONTINUOUS PLANT FOR TREATING FIBER

Filed May 29, 1929

UNITED STATES PATENT OFFICE

BERTRAND S. SUMMERS, OF EVANSTON, ILLINOIS

CONTINUOUS PLANT FOR TREATING FIBER

Application filed May 29, 1929. Serial No. 366,857.

Raw fiber, such for example as sisal and manila, must be processed through a certain number of steps, such as decortication, drying, etc., before it is ready for baling and shipment to mills for its further manufacture into twine, cordage, rope, and the like. As at present practiced, these preliminary, preparatory steps require the material to be excessively handled, which is, of course, objectionable in several respects.

To overcome such excessive handling, this invention provides a continuous plant for converting fibrous substances in their raw state to the finished product, ready for the factory. Thus, the invention relates to both a structure, or combination of structures, and a method of handling raw fiber.

The primary object is to provide a combination of machines consisting of a cleaning mechanism, a separating mechanism, a squeezing mechanism, and a drying mechanism, the several units of the system being connected together to form a continuous mechanism whereby the fibrous material is converted from the raw state to the finished product without manual manipulation. While this is primarily designed for sisal and manila, it may be used with other material subject to similar operation.

Another object is to provide a novel method of handling raw fiber.

In the drawings:

Figure 1 is a general top plan view of the continuous plant; and,

Figure 2 is a general side elevational view of the same structure.

A feeder table 1 is provided for driving the stems or leaves of the fibrous material to the cleaning machine. Numeral 2 designates a conventional cleaning machine, which embodies a set of conveying chains 2^a for drawing the fiber through cleaning drums and then delivering the same in such a way that the tip or taper ends of the fiber lie in a vertical position, while the butt ends are more or less in a horizontal position. The fibers are so shown emerging at 2^b.

The fibers 2^b are caused to be deflected by a shield 3 around and over a vertical shaft comprising a set of superposed, spaced pulleys 4

operating in horizontal planes. These pulleys are the charging end of a spreader and conveyer device generally indicated at 5, which comprises the subject-matter of a separate patent application filed May 29, 1929, and bearing Serial Number 366,858. This device functions to change the fibers from their vertical position to a horizontal position, so that these fibers may be laid on the conveyer of a succeeding squeezing machine crosswise of the direction of movement of such conveyer. This spreader and conveyer device also embodies a horizontal shaft which carries a series of spaced, vertically running pulleys 6. The pulleys 4 and 6 are arranged in cooperating pairs, and, trained around each pair is an endless, flexible element, such as the ropes 6^a. These ropes constitute the spreader and conveyer. The fiber leaves this device arranged transversely of its direction of travel, and in this manner is deposited from the chute 7 onto the feeder conveyer 8 of a squeezer generally indicated at 9. This squeezer is disclosed in a copending patent application filed May 29, 1929, and bearing Serial Number 366,855.

The conveying apron 8 of the squeezing mechanism meets an upper apron 9^a and is conveyed through one or more nips between rolls under heavy pressure to squeeze moisture from the fiber between the aprons, and the fiber is finally delivered onto a chute 10, which chute discharges onto an apron 11 of a drying mechanism generally indicated at 12, the said apron conducting the fibrous material through the drying mechanism and delivering the dried fiber in a dried condition without massing or tangling the fibers. This drying mechanism constitutes the subject-matter of another copending patent application filed May 29, 1929, and bearing Serial No. 366,856.

Figure 2 shows the assembly in elevation, and it will readily be seen how the path of the fiber is continuous in one direction, which insures conducting the fiber in a uniform neat layer throughout the several mechanisms without manual handling.

The method of handling fibers thus consists in the steps of feeding fibrous material to a

cleaning mechanism, arranging and spreading the cleaned fibers crosswise of a longitudinally moving conveyer, conveying the material in this manner through a squeezer to remove water therefrom, and, lastly, passing the material in the same crosswise manner on a conveyer through a drying mechanism to dry the same.

Having now described my invention, what I claim as new is:

- 10 1. The combination of a cleaning machine adapted to receive fibers and discharge them in vertical position, a spreading and conveying device for receiving the fibers in their vertical position and for moving them to horizontal positions crosswise of a longitudinally moving conveyer, a squeezing device receiving the fiber from the spreader and conveyer, and a drying device so connected in the line that one machine passes the layer of fiber to the next one without manual manipulation substantially as described.
- 15 2. In combination, a series of fiber treating machines consisting of a cleaning mechanism delivering fibers in vertical planes, a spreading and conveying mechanism for delivering the fiber in a horizontal plane, a squeezing mechanism for squeezing the fiber lying in the said horizontal plane and crosswise of the machine, and a drying mechanism for drying the fiber, the units being connected by conveyers in such a way that manual manipulation is avoided.
- 20 3. A combination of fiber treating machinery consisting of a cleaning or decorticating mechanism, a conveyer having means for receiving fibers in a vertical plane and delivering the fibrous material in a horizontal plane, a water extracting mechanism for extracting water from fiber lying crosswise of the direction of motion, and a drier for receiving the fiber in said position without manual manipulation substantially as described.
- 25 4. A continuous plant for treating fiber, said plant comprising a cleaning machine having means for conveying cleaned fiber in a vertical position, a squeezer, means between the cleaning machine and squeezer for receiving the vertical fiber from the cleaning machine and laying it in a crosswise horizontal position and so delivering it to the squeezer, a drier, and means for delivering the fiber in crosswise position from the squeezer to the drier.

55 In testimony whereof I affix my signature.
BERTRAND S. SUMMERS.
